UNITED STATES PATENT OFFICE.

CARL J. ANDERSON, OF CHICAGO, ILLINOIS.

ELEVATOR CONTROL.

Application filed January 19, 1923. Serial No. 613,591.

To all whom it may concern:

Be it known that I, CARL J. ANDERSON, a citizen of the United States of America, and a resident of Chicago, county of Cook, and 5 State of Illinois, have invented certain new and useful Improvements in Elevator Controls, of which the following is a specification.

My invention relates to controllers for 10 electrically operated elevators, and has for its object improvement in such devices.

In the accompanying drawings—

Fig. 1 is a front elevation of the device;

Fig. 2 is a section on line 2—2 of Fig. 1;

15 Fig. 3 is a partial side elevation;

Fig. 4 is a diagram of a four-floor installation with the elevator represented as standing at the first floor;

Fig. 5 represents the same parts when the 20 elevator is standing at the second floor; and

Fig. 6 is a diagram of so much of the general electrical connections as is necessary to an understanding of the control of the elevator.

25 The device is secured to, and partly contained in, an open faced box 11 which is provided with lugs 12 by which it is secured in the elevator shaft adjacent to the elevator moving therein. There is a device like 30 that of Fig. 1 at each intermediate floor, and a simplified form of the same device at the top and bottom floors.

Inside of the box 11 is a piece of insulating material 13, and secured thereto near 35 the center is a bracket 14 which is provided with studs 15 and 16. Pivoted upon these are arms 17 and 18, each of which is provided with a contact end 19 and a roller 20. Between the arms 17 and 18, is a spring 21 40 which acts to press the arms apart and brings their ends 19 against studs 22 and 23, which are electrical terminals.

On the extension 24 of box 11 is a stud 45 25, and on this stud are pivoted levers 26 and 27, each of which has a cam arm 28 and a roller-carrying arm 29. Between the arms 28 is a spring 30 which acts to push these arms apart, but this movement is limited by the part 31 on one arm engaging part 32 on the 50 other. (Fig. 3.) The extreme distance arms 28 may be moved from each other is that 55 represented in Fig. 1. In this position the arms may be oscillated back and forth on the stud 25, the limits of which oscillation are determined by the levers 26 and 27 striking parts 33 on extension 24. In this

operation, the levers 26 and 27 are sections of a lever pivoted on the stud 25.

On the arms 28 are cams 34 and 35, and adjacent surfaces 36 which are arcs of circles having the stud 25 for a center. When the levers 26 and 27 are in the position shown in Fig. 1, the surface 36 on lever 26 acts on roller 20 of arm 17 to hold contact 19 of that arm away from the adjacent electrical terminal 22. The roller 20 on arm 18 being free from cam 34 and its adjacent surface 36, is pushed by spring 21 so that its contact end 19 engages terminal 23. When levers 26 and 27 are moved to their other extreme, the cam 34 first engages roller 20 to break the electrical connection of arm 18, and immediately thereafter cam 35 releases its roller 20 so that spring 21 may move arm 17 to electrical connection with terminal 22. In this operation there is a brief interval 75 during which the connections are broken to both 22 and 23.

On the arms 29 of lever sections 26 and 27 are rollers 38 and 39, and on the side of the 80 elevator car is a cam 40 arranged to engage these rollers as the car moves up and down. (Figs. 1, 4 and 5.) This cam is so located that it pushes a roller 38 or 39 to its extreme inward position, and is long enough 85 to engage both rollers at the same time as shown in Fig. 5. If we assume the cam 40 of Fig. 1 to be moving downward in a line parallel with its face, the said cam holds the roller 38 and then strikes the roller 39, moving it inward on its pivot 25. In this action the spring 30 is compressed, and cam 34 strikes its roller 20 to move arm 18 so as to break electrical connection at 23. If the car stops in this position, the electrical 90 connection is broken at both 22 and 23. But if the car continues on down, then cam 40 releases roller 38 and spring 30 expands to release arm 17, and spring 21 acting on this arm makes a new connection at 22.

The arm 17 and roller 38 represent control of the car when moving upward, and arm 18 and roller 39 represent control for it when moving downward. As the car comes to the first floor only by moving downward, and to the top floor only by moving upward, only one arm and roller are needed for each of these places. But for intermediate floors, two arms and rollers are needed as the car comes to these floors in both upward and downward movements.

The general electrical arrangement is

shown in Fig. 6, in which I, II and III represent the lines leading to the source of electrical power, and 100 represents a motor for driving the elevator. The magnet 41 serves to connect contact 42 to contact 43, and contact 44 to contact 45 for starting the motor 100 in the proper direction to move the elevator upward. The magnet 46 serves in a similar manner to connect 47 to 48, and 49 to 50, for moving the elevator downward. The magnets 41 and 46 may be solenoids for moving levers as shown in my Patent No. 1,318,845, issued October 14, 1919. 51 is a break magnet which need not be considered here as it forms no part of the present invention.

The selecting magnets for the different floors are shown at 52, 53, 54 and 55 and may be of any convenient construction for 20 making and breaking connections as will be described. The push buttons in the hall are represented by 1^a, 2^a, 3^a and 4^a. The corresponding buttons in the car are represented by 1^b, 2^b, 3^b and 4^b.

25 In Figs. 4, 5 and 6, the arms 17 are represented by the letter U to indicate the upward movement, and the arms 18 are represented by the letter D to indicate downward movement. Assuming that the elevator is standing at the first floor, and that a person wishes the elevator to go to the third floor, he pushes the button 3^a. A current will then flow from line I to contact 42, then thru line 60—resistance 61—62—63—35 3^a—64—spring 65—contact 66—67—54—68 to the U-lever for the third floor 69—70—71—72—73—41—74—44—line III.

This current thru magnet 41 operates it to connect contacts 42 to 43, and also 44 to 45 so as to connect motor 100 to lines I and III and start said motor to raise the elevator. At the same time magnet 54 moves its lever 56 to break the connection between 65 and 66 and remake it between 45 56 and 66. The current then goes from 60 to 75, 56, 66 and so on. This shunts the button 3^a and holds the circuit independent of whether the operator holds the button closed or not. It also shunts the resistance 61.

The connections just described are held during the rise of the elevator. When the elevator is arriving at the second floor, the cam 40 first engages wheel 39 to hold it and then engages wheel 38 to break the connection of the U-lever at this landing. But as the circuit was made thru the U-lever of the third floor, this break at the second floor affects nothing. When the car leaves the 60 second floor it leaves the D-lever in contact with its adjacent contact terminal, but the U-lever has its connection broken. When the car reaches the third floor, the circuit for magnet 41 is broken at the U-lever for 65 this floor, and this in turn breaks the cir-

cuit for the motor and stops the car, with connections broken at both levers. This condition is shown for the second floor in Figs. 5 and 6.

Assuming that the elevator is standing 70 at the second floor, as in Figs. 5 and 6, it will be evident that pressing the button for the third floor will produce the same result as before except that the elevator will move only the distance from one floor to the next. If the button for the first floor should be pressed when the elevator is standing at the second floor, then the circuit would go thru the selecting magnet 52, the D-lever of 75 the first floor and the magnet 46 for starting the motor to move the elevator in the downward direction.

What I claim is:

1. In a device of the class described, two pivoted levers, a spring acting on said levers so that they normally move as a single lever but each lever being movable with respect to the other by compression of said spring, and electrical terminals controlled by the 85 movements of said levers.

2. In a device of the class described, two levers mounted upon a common pivot, a spring acting on said levers so that they normally move as a single lever pivoted on its center, said spring being adapted to yield 95 so that either lever may be moved with respect to the other, and electrical terminals controlled by the movements of said levers.

3. The combination with an elevator car, and a cam thereon, of a lever composed of 100 two sections mounted upon a common pivot, a yielding connection between said sections and serving to cause them to normally operate as a single lever on a pivot, rollers on said sections engaged by the cam on a 105 passing car, said parts being so arranged that the cam will move one section with respect to the other and later permit the second to move to normal relationship so that the sum of the two movements will 110 be a reversal of the lever on its pivot, and electrical connections operated by such movements.

4. The combination with an elevator car, and a cam thereon, of a lever composed of 115 two sections yieldingly connected together, a pivotal support for the lever, means by which upon a car passing the lever the cam thereon will cause a movement of the lever sections one at a time so as to leave the 120 lever moved on its pivot to a new position, and electrical connections controlled by the lever and in turn controlling the car.

5. The combination with an elevator car, and a cam thereon, of a lever composed of 125 sections yieldingly connected together, a pivotal support for the lever, a circuit closing device for each section, the open or closed condition of which device is determined by the position of the section, and 130

means by which upon a car passing said lever the cam on the car will move one section to open its electrical connection and later permit the other section to move so as to close its electrical connection, said last movement being by action of the yielding connection put under strain by the movement of the first section.

6. The combination with an elevator car, 10 a cam thereon, and two contact closing devices one of which controls the upward movement of the car and the other of which controls the downward movement thereof, of a lever composed of two sections each 15 of which controls one of said contact closing devices, a pivot upon which said sections are independently movable, and a spring connecting the sections and serving to hold them normally in a definite relationship to each other yet adapted to yield 20 so that either section may be moved with respect to the other, said parts being so constructed that upon a car passing a lever the cam will hold one section and then move the other to compress the spring and will then hold the second and release the first so that said spring may move it.

7. In an elevator system, an elevator car and a motor for raising and lowering it 25 thru the distance of several floors, a pair of contact closing devices at each intermediate

floor, one of which devices is always open and the other closed when the car is at any other floor, connections from the contact closing devices for controlling the motor 35 circuit, and means operated by the moving car for reversing the open and closed condition of said contact closing devices as the car passes from one side of the floor to the other.

8. In a device of the class described, two independently movable contact devices, a spring located between said devices and under strain to move them toward closed position, mechanism arranged to hold one of them always open, means for operating said mechanism to open the closed device and to put further strain on said spring, and further means for releasing the previously open device so that the spring may close it. 40 45

9. In a device of the class described, two independently movable contact closing devices, a spring located between said devices and under strain to move them toward closed position, a lever having two independently movable sections each being provided with means for opening the corresponding contact closing device, and means by which the sections are operated in succession to cause successive movements of the 50 55 contact closing devices.

CARL J. ANDERSON.
